(57) **CLAIM**

The ornamental design for an electronic lock box, as shown and described.

DESCRIPTION

FIG. 1 is a top, front, and right side perspective view of an improved electronic lock box with its key compartment closed, showing my new design.

FIG. 2 is a top, rear, and left side perspective view of the electronic lock box of FIG. 1, with its key compartment closed.

FIG. 3 is a front, elevational view of the electronic lock box of FIG. 1.

FIG. 4 is a rear, elevational view of the electronic lock box of FIG. 1.

FIG. 5 is a right-hand side, elevational view of the electronic lock box of FIG. 1.

FIG. 6 is a top, plan view of the electronic lock box of FIG. 1.

FIG. 7 is a bottom, plan view of the electronic lock box of FIG. 1.

FIG. 8 is a top, front, and right side perspective view of the electronic lock box of FIG. 1, with its key compartment open; and,

FIG. 9 is a top, front, and right side perspective view of the electronic lock box of FIG. 1, with its shackle removed. The left-hand side of the electronic lock box is a mirror image of the right-hand side depicted in FIG. 5.

The broken lines on FIGS. 1-9 are used to show unclaimed portions of the lock box.
